POLISH ROD HOLDER

Filed Sept. 13, 1927

Attorney

UNITED STATES PATENT OFFICE

JOHN N. MARTIN, OF FORT WORTH, TEXAS

POLISH ROD HOLDER

Application filed September 13, 1927. Serial No. 219,336.

Modern oil well pumping installations of the ordinary standard rig type, without counterbalance, include in addition to a derrick, an engine of some sort for operating a walking beam which actuates a pump, the piston of which is actuated through sucker rods and a polish rod which last extends up through a stuffing box and has a releasable hanger connection with the walking beam. Owing to the contraction, expansion, or stretch in the sucker rods by which the valve and polish rod are united, or to slipping of the hanger connections on the polish rod, or for other reasons, it is necessary to space the hanger connections on the polish rod periodically. In order to effect such spacing in an upward direction, the polish rod is raised from its bottom of stroke position by means of the engine and walking beam, and while being held in such position, some means, which rests on the stuffing box, is applied to the polish rod to hold it in that position independent of the hanger connections between the polish rod and beam. The hanger end of the beam is then lowered to its bottom of stroke position, thus throwing slack in the hanger connections which are loosened on the polish rod and fastened at a lower position. The holding means is then released, allowing the rods to drop the short distance to take up the slack in the hanger connections to the beam which then holds the weight of the rods ready to begin pumping.

It must be understood that to raise the polish rod above the bottom of stroke position by use of beam and engine and to hold it approximately in a given position, requires the continuous attention of the operator at the engine controls to maintain a balance of power; otherwise full pumping motion will begin, or the weight of the string of rods will pull the beam down to the bottom of stroke position. Further it must be understood that the engine controls are located several feet away from the polish rod, and it is impossible for a man to reach both at the same time. Therefore in spacing wells upward heretofore the holding means has been in the form of a clamp, the application of which to the polish rod required the attention of two men,

one at the engine controls, and the other at the clamp. The presence of two men is not always available when the emergency for spacing occurs.

It is the object of this invention to provide a one man polish rod holder for spacing rods upward and for other purposes.

It is therefore obvious that this holder must be self-engaging upon the polish rod when, by means of the engine and beam, the operator raises the rod string above the bottom of stroke position. Also, it must be releasable from the polish rod without the necessity of again raising the rods, and since, after spacing there will be some slack in the hanger connections, the weight of the rods will be upon the holder and it must therefore be releasable with this load upon it. This necessity of releasing the hold of the wedges upon the polish rod while the strain or load of rods is upon the wedges, arises in this device. All other oil field tools employing wedges or slips release by raising the held object, because no means of releasing is necessary.

The invention consists of a pair of blocks or jaws, connected at one of their ends in such way as to be movable toward and from one another, the jaws being provided with adjacent tapering recesses which when the jaws are brought together form a substantially continuous opening through the jaws, from top to bottom, in which opening are arranged wedges having exterior tapering surfaces to match the tapering recesses in the jaws and having recesses adapted to fit the polish rod and made with smooth parallel rod-engaging faces so as not to mar the surface of the polish rod; the wedges, like the jaws, being halved so that they may be applied to the polish rod in a transverse direction; the jaws being provided with locking and releasing means by which they may be used to hold the wedges about the rod in such way that the rod may be supported by the jaws resting upon the stuffing box, as I will proceed now to explain more fully, and finally claim.

In the accompanying drawings illustrating the invention, in the several figures of which like parts are similarly designated, Figure 1 is a perspective view, showing the holder

of this invention applied to a portion of a 5 polish rod. Fig. 2 is a partial longitudinal section. Fig. 3 is a transverse section. Fig. 4 is a view similar to Fig. 2, showing a modification in the means for arresting undue descent of the wedges upon opening of the release mechanism. Fig. 5 is a perspective view of another such modification.

In the illustrative instance of my invention, 10 as shown in Figs. 1 and 2, there are two similar jaws 1 and 2, having a knuckle hinge joint 3, by which they are connected; although other means may be used for connecting the 15 jaws. Opposite faces of the jaws have the unbroken uniform semicircular tapered recesses 4, extending from top to bottom, which when the jaws are closed upon one another form a tapered hole extending through the 20 jaws from top to bottom. The top and bottom, and especially the bottom of the jaws, are made flat so as to rest securely and without tilting on the stuffing box of the pump through which the polish rod 5 extends.

In the recesses 4 are placed the polish rod- 25 engaging means, consisting of wedges 6, semicircular in cross section and having the plain parallel semicircular smooth surfaces 7 on the inside to correspond with the diameter and smooth surface of the polish rod, and adapted to engage a maximum adjacent surface of the 30 polish rod frictionally and without liability of marring it. The exterior or outer surfaces of the wedges are tapered complementally with the recesses 4 and of uniform unbroken 35 contour.

These wedge sections may be held between the 40 jaws without liability to too great descent in their recesses, upon opening of the release mechanism by any of a variety of means, such as the top flanges 8, as shown in Figs. 1, 2 and 3; or the bottom of the recesses 4 of the jaws may be provided with a shoulder 45 9, as shown in Fig. 4; or, as shown in Fig. 5, the wedges may be provided with laterally extending pins 10, to cooperate with the upper 50 surfaces of the jaws.

In order to prevent the loss of the wedges, 55 they may be connected to the jaws by means of chains 11, as shown in Fig. 1, or other suitable means.

The jaws are locked together by any suitable quick-acting locking and releasing means, such as a release screw 12, extending 60 from a head 13 which is arranged to turn in a recess 14 in one of the jaws and held therein by a pivot pin 15, the screw extending through a notch 16 in the other jaw and provided with a wing or lever nut 17, so that upon sufficient loosening of the nut the screw 65 may be readily moved out of the notch 16 and rotated on its pivot 15 clear of the notched jaw, whereby the jaws may be opened and removed from the polish rod along with their wedge members.

65 The jaws may be made of considerable

thickness, as indicated in Fig. 3, or may be of less thickness and reinforced by longitudinally extending ribs 18, as shown in Fig. 1.

The holder may be released from the polish 70 rod while the load is still upon said rod, by simply unscrewing the release screw 12, thereby allowing the jaws to be moved apart sufficiently to release the grip of the wedges upon the polish rod.

When the holder is applied and the polish 75 rod is lifted, the holder will immediately engage the polish rod as it begins the downward movement and hold it fast.

It will be understood that when it becomes necessary to respace the rods in a pumping 80 well in an upward direction, or the hanger connections in a downward direction, it is requisite to stop the pumping movement, raise the polish rod the required distance, clamp it up in that position, disconnect the 85 hanger connections and reconnect them at a lower position on the polish rod. This generally requires the continuous attention of one operator until the clamp is firm upon the polish rod and able when resting upon the 90 stuffing box to hold the weight of the rods. The clamp is then released, dropping the load of the string of rods on the hanger connection to the beam and all the parts in readiness to begin pumping again. By my invention as the operator handles his engine or 95 motor controls to raise the polish rod to the required position, the holder will engage and hold the polish rod in that position, whereas with the common type of clamp, it is necessary to have a second man to screw up the 100 clamp tight on the rod to hold the weight.

It is to be noted also that my holder may be released without the necessity of raising or taking off the load of the rods. The 105 holder will have its center of gravity approximately at the center line of the polish rod, which latter it will grip so that it will set evenly upon the stuffing box of the well, without tendency to tip sidewise.

The wedges will be of proper taper and weight to engage the polish rod immediately upon down movement of the polish rod and yet not grip or hold upon the initial up movement of the polish rod.

The value of the non-marring feature of the holder is that the polish rod retains its smooth finish and consequently does not tear or rapidly wear out the packing in the stuffing box.

Any suitable auxiliaries may be used to assist or force the engagement of the wedges with the polish rod.

Variations in the details of construction may be made within the principle of the invention and the claim following.

What I claim is:—

A polish rod holder, for oil well and similar pumps, comprising a pair of similar holding jaws, hingedly connected at one end and 120

provided at their other end with a jaw-locking and releasing means consisting of a screw having a head pivotally mounted in one of the jaws and adapted to be swung into and out of engagement with a notch in the other jaw and provided with a nut engaging the thread of the screw and bearing upon the outer surface of said notched jaw and capable of quickly closing and releasing the jaws by turning the nut and swinging the screw on its pivoted head, the opposite faces of the jaws having semicircular tapered recesses of uniform unbroken contour extending from top to bottom of the jaws, and polish rod engaging means consisting of wedges semicircular in cross-section and having the plain parallel semicircular smooth surfaces on the inside corresponding with the diameter and the smooth surface of the polish rod to be held and released at pleasure and tapered and unbroken outside surfaces to match the surfaces of the recesses in the jaws, the locking and releasing means being operable to release the rod from the holder while the weight of the string of rods is upon the holder and without the necessity of raising the polish rod up through the holder, so that one man may perform, without the aid of an assistant, all of the operations to space upward the string of rods in an ordinary pumping well of standard rig type without counterbalance.

In testimony whereof I have hereunto set my hand this 12th day of September, A. D. 1927.

JOHN N. MARTIN.
